CLAIM

The ornamental design for a multiple push-button switch module, as shown and described.

DESCRIPTION

FIG. 1 is a front and lower right perspective view of a multiple push-button switch module showing our new design;

FIG. 2 is a rear and upper left perspective view thereof;

FIG. 3 is a front elevational view thereof;

FIG. 4 is a right side elevational view thereof;

FIG. 5 is a top plan view thereof, the bottom plan view thereof being a mirror image;

FIG. 6 is a rear elevational view thereof;

FIG. 7 is a left side elevational view thereof;

FIG. 8 is a front and lower right perspective view of a multiple push-button switch module showing a second embodiment of our new design, the plan and elevational views being the same as the first embodiment except for the number and location of push-button members; and, FIG. 9 is a front and lower right perspective view of a multiple push-button switch module showing a third embodiment of our new design, the plan and elevational views being the same as the first embodiment except for the number and location of push-button members.

FIG. 1

FIG. 2

FIG. 3

FIG. 4

FIG. 5

FIG. 6

FIG. 7

FIG. 8

FIG. 9
